AIRCUSHION VEHICLE

Harry A. Laufman, 1510 E. Colorado Blvd.,
Glendale, Calif. 91204

Filed Mar. 16, 1970, Ser. No. 21,914

Term of patent 14 years

Int. Cl. D12—⁷²

U.S. Cl. D71—1

FIG. 1 is a perspective view of an air car showing my new design;

FIG. 2 is a front elevation of the air car shown in FIG. 1;

FIG. 3 is a rear elevation of the air car shown in FIG. 1; and

FIG. 4 is a left-side elevation of the air car shown in FIG. 1.

I claim:

The ornamental design for an aircushion vehicle, substantially as shown.
